BUILDING SIDING PANEL

William Waldman, East Orange, N. J., assignor to Brixite Manufacturing Co., Inc., South Kearny, N. J., a corporation of New Jersey

Application October 6, 1953, Serial No. 27,088

Term of patent 14 years

(Cl. D68—1)

Fig. 1 is a front view of a building siding panel showing my new design;

Fig. 2 is a horizontal section taken approximately in the plane of the line 2—2 of Fig. 1; and

Fig. 3 is a vertical section taken approximately in the plane of the line 3—3 of Fig. 1.

I claim:

The ornamental design for a building siding panel, substantially as shown.
